TRAILER OR SIMILAR ARTICLE

Stanley N. Lewis, Gardena, Calif.

Application January 16, 1956, Serial No. 39,807

Term of patent 14 years

(Cl. D14—3)

The opposite side elevational view of the trailer is the same as the view of Figure 1 reversed end for end. The over-all effect of the end opposite that shown in Figure 2 is the same as in Figure 2.

The characteristic features of my design for the trailer disclosed reside in the siding having the configuration and appearance shown.

I claim:

The ornamental design for a trailer or similar article, substantially as shown and described.
